(57) **CLAIM**

The ornamental design for a hacksaw frame, as shown and described.

DESCRIPTION

FIG. 1 is a perspective view of a hacksaw frame showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is the first perspective view of a hacksaw frame in use state;

FIG. 9 is the second perspective view thereof in use state; and,

FIG. 10 is the third perspective view thereof in use state. The broken lines in FIGS. 1, 4-7 illustrate portions of the hacksaw frame and the broken lines in FIGS. 8-10 showing a hacksaw frame are for the purposes of illustrating environment, all broken lines form no part of the claimed design.
